UNITED STATES PATENT OFFICE

WILLIAM C. KRAUTHEIM AND KARL S. HOWARD, OF ST. LOUIS, MISSOURI, ASSIGNEES
TO GENERAL STEEL CASTINGS CORPORATION, OF GRANITE CITY, ILLINOIS, A
CORPORATION OF DELAWARE

LOCOMOTIVE BED

Application filed March 2, 1931. Serial No. 519,587.

Our invention relates to railway rolling stock and consists in a novel locomotive bed or underframing structure.

The main object of our invention is to produce a bed which is rigid so as to avoid undesirable play between operating parts mounted thereon and which, preferably, is of integral structure so as to avoid the time and expense required for preparing separately formed parts for assembly with each other and to avoid the time and expense required for frequent inspection and maintenance as is required for keeping built-up structures rigid.

It is an additional object of our invention to produce a bed by casting all or a substantial part thereof in a one piece casting and, with this end in view, we desire to eliminate unnecessary cores for the casting mold and to avoid the use of cores of small dimensions.

It is a further object of our invention to provide structure for supporting a cylinder intermediate the sides of the frame, and above the level thereof, and structure for supporting a boiler integral with the frame and to brace the upwardly projecting structure from the frame adjacent to the cross head supporting portion of the latter.

Other detail objects of our invention will appear from the following description and the accompanying drawings in which—

Figure 1 is a top view of one longitudinal half of our novel frame with a portion of its rear end broken away.

Figure 2 is a side elevation of the same.

Figures 3 to 18 inclusive are vertical transverse sections taken on the corresponding section lines of Figure 2.

Figures 19 and 20 are vertical longitudinal detail sections taken on the corresponding section lines of Figure 1.

Figure 21 is a top view of one longitudinal half of the bed illustrating a modified form of our invention.

Figure 22 is a side elevation of the same.

Figures 23, 24, and 25 are vertical transverse sections taken on the corresponding section lines of Figure 21.

The bed is of the general type described in Patent No. 1,780,466, issued November 4, 1930 to G. F. Driemeyer and E. C. Jackson,

in which a main load-carrying and longitudinal force-transmitting backbone member is provided with wheel pieces at the sides thereof for forming pedestals for receiving the driver boxes and for mounting the spring equalizing fulcrums and other equipment.

The accompanying drawings illustrate a form of the invention adapted for six pairs of drivers indicated at 1, 2, 3, 4, 5, and 6. The main box section backbone member of the frame extends abreast of drivers 3, 4, 5, and 6 and comprises side walls 51, a top wall 52 and a bottom wall 53. The channel shaped wheel pieces at the side of the center box member comprise webs 54 and flanges 55 and 56, the flanges being turned inwardly and merging with the adjacent side walls 51 of the center member. Suitable openings 7 are provided in flanges 55 and 56 at intervals to lighten the casting.

Pedestal legs 8 extend downwardly from the wheel pieces and the adjacent legs of successive pedestals are connected by suitable integral braces 9. Preferably the pedestal legs and their braces and the upright portions of the wheel pieces are of solid section and thereby we eliminate a substantial amount of difficult pattern and core work provided by the construction shown in said Driemeyer and Jackson patent. The structure also includes reinforcing webs 10 and transversely disposed cross ties 11 and suitable brackets for brake fulcrums, hangers, equalizer fulcrums and similar equipment are shown at 12, 13, and 14, respectively. At 16 are expansion sheet brackets and at 17 are brake cylinder brackets, all of these parts being integral with the main members of the bed.

The center box member terminates adjacent to the forward pedestals of the drivers 3 and the space between the pedestals of the second pair of drivers 2 is left open, as indicated at S, to accommodate the connecting rod and crank (not shown) for the center cylinder 18. At this point, the flanges of the wheel pieces are eliminated, leaving a rectangular slab member 19 (see Figure 9). In front of the forward driver 1 the wheel piece takes the form of lower and upper elements

20 and 21 having a **U** section and an inverted **U** section, respectively. The lower element 20 gradually merges into a box section 22 between the cross head guide bracket 23 and the main steam cylinder 24. The cylinder and smoke-box saddle structure includes a boiler support 25 and a hollow inverted **U** shape brace 26 extends from the boiler support 25 downwardly to the side member where the cross head bracket is located. The forward portion of the bed, shown in Figure 3, consists of a comparatively shallow box with side walls 27, top wall 28, bottom wall 29 and an intermediate vertical reinforcing web 30.

5 The main steam cylinder and boiler supporting saddle structure in itself does not constitute our present invention but is described and claimed in the copending application of C. W. Kell, filed March 6, 1931, Serial No. 520,510.

10 At the rear end of the box center member, the lower wall 33 extends downwardly (see Figure 19) and includes a trailer truck fulcrum element 31. The sides of the member are inclined inwardly and merge with each other at 32 to form adequate support for element 31.

15 In addition to the objects and advantages 30 of the above described structure which have previously been pointed out, if it is desired to standardize the outside dimensions of the channel wheel pieces and, at the same time, vary their section and strength, the cores between these wheel pieces and the center member can be made larger or smaller, as required.

20 The construction illustrated in Figures 21 to 23 substitutes side members 40 of solid section throughout the length of the center member 41 and further simplifies the formation of a mold for a cast bed. This structure is particularly advantageous on a shorter bed, although it may be used, if desired, on longer beds. Pedestal legs 42 are also of solid rectangular section and are connected by lower braces 43 of similar cross section. A lower member 44, of similar section, extends forwardly from the front pedestal and with member 40, and an upright web 45, forms a connecting structure between the pedestal portion of the bed and the portion carrying the main steam cylinders 46. As in the preferred structure, the wheel pieces include suitable brackets 47, 48, and 49 for mounting the usual equipment thereon.

25 Various other modifications in the details and arrangement of the bed structure embodying the invention may be made without departing from the spirit thereof and we contemplate the exclusive use of the novel features described herein as set forth in the accompanying claims.

We claim:

30 1. In a locomotive bed, a main center mem-

ber of box cross section, and driver wheel pieces, at the sides thereof, of channel cross section having pedestal legs depending therefrom, the flanges of said wheel pieces being united with said center member.

5 2. A locomotive bed as described in claim 1 comprising an integral structure free of joints between overlapping elements of the parts mentioned.

3. A locomotive bed as described in claim 1 75 in which the side walls of the center member are relatively thin and the webs of the wheel pieces are relatively thick.

4. A locomotive bed as set forth in claim 1 80 consisting of a casting in which the flanges of the channel wheel pieces are turned towards the center member to provide a maximum space between the side wall of the center member and the web of the wheel pieces to facilitate the coring and cleaning of the casting.

5. In a locomotive bed, side members having portions for carrying main steam cylinders and cross head guide brackets, a boiler support spaced substantially above said cylinder carrying portions, and braces extending between said support and said bracket carrying portions.

6. A locomotive bed as described in claim 5 85 consisting of an integral structure in which said side members of said braces are of hollow construction.

7. A locomotive bed as described in claim 5 90 consisting of an integral structure in which said side members are of box cross section and said braces are of inverted **U** section.

8. A locomotive bed side frame having a cross head guide bracket integral therewith and, adjacent to said bracket, comprising an upper member of inverted **U** section and a lower member of **U** section spaced therefrom, a boiler support spaced above said frame and longitudinally of said bracket, and an inverted **U** shape brace extending downwardly and rearwardly from said support and merging with said frame upper member.

9. A locomotive bed having a main center member of box section including a trailer truck fulcrum element near its rear end, the side walls of said member being inclined inwardly and merging with each other over said element.

10. A locomotive bed as described in claim 9 100 which includes slab-like cradle sides extending rearwardly of said center member, and elements uniting said center member and sides, all of said parts constituting an integral structure.

11. In a locomotive bed, a center back bone 105 member, a wheel piece spaced from said center member and including pedestal legs depending therefrom, said center member being of box shaped cross section and said wheel piece being of solid cross section.

12. In a locomotive bed as described in claim 11, elements connecting said center member and wheel piece, the entire structure being an integral unit.
- 5 13. A locomotive bed comprising a single integral casting having spaced side members of relatively thick solid section and having connecting members of relatively thin section merging with said side members.
- 10 14. A locomotive bed comprising a single integral casting having spaced side members including pedestals, and connecting members between said side members and pedestals, said side members and pedestals having relatively thick solid sections, and said connecting members having relatively thin sections and merging with said side members.
- 15 16. In a locomotive bed, a main center member of box cross section, and channel shape driver wheel pieces at the sides of said box section, the webs of said wheel pieces being spaced from the sides of said center member and the flanges of said wheel pieces merging with said center member, the webs of said wheel pieces being thicker over the driver box openings than they are intermediate said openings.
- 20 17. In testimony whereof we hereunto affix our signatures this 24th day of February, 1931.
- 25
